UNITED STATES PATENT OFFICE

LEO DEUTSCH, OF BEAVER, PENNSYLVANIA

APPARATUS FOR CLEANING CONTAINERS

Application filed September 2, 1927. Serial No. 217,023.

This invention relates to an apparatus for cleaning containers and the like, and more particularly to a motor vehicle service station unit for cleaning gear casings and the like.

5 One object of the invention is to provide such an apparatus which shall be very simple in its construction and operation, which will comprise but a few parts, and which will require but little attention to maintain the same 10 in operative condition.

A further object of the invention is to provide in such an apparatus an ejector having means for increasing the efficiency thereof.

A further object of the invention is to provide 15 such an apparatus so constructed that the greasy fluid withdrawn from the gear casing and discharged into the container will not foam to an objectionable extent.

A further object of the invention is to provide 20 in such an apparatus improved means for supporting the pump within the container.

A further object of the invention is to provide 25 in such an apparatus improved means for keeping the strainer clean.

Other objects of the invention will appear as the apparatus is described in detail.

In the accompanying drawings Fig. 1 is a 30 side elevation, partly in section, of an apparatus embodying my invention; Fig. 2 is a section taken vertically through the pump and the inlet casing, Fig. 3 is a front elevation of the upper portion of the apparatus showing the ejector; and Fig. 4 is a transverse section taken on the line 4-4 of Fig. 1.

In these drawings I have illustrated one embodiment of my invention, but it will be understood that the particular embodiment here shown has been chosen for the purposes 40 of illustration only and that the varicous parts of the apparatus may take different forms and may be arranged in different ways without departing from the spirit of the invention.

45 In that form here illustrated the apparatus comprises a container 5 for cleaning fluid, such for example, as kerosene, and which is preferably cylindrical in form and the top wall 6 of which is removable and constitutes 50 a closure and also a support for various

parts of the mechanism. Mounted on the container 5 is a pump which in the present instance is supported within the container from the top of wall 6 thereof and which is preferably a rotary pump, as shown at 7. 55 The intake of the pump is immersed in the fluid within the container, and the discharge pipe 8 leads from the pump through the top wall 6 and is connected with a pressure line which is preferably in the form of a flexible 60 conduit or hose 9 adapted to have its discharge end inserted in the casing to be cleaned. If desired, the discharge end of the conduit may be provided with a nozzle 10 having a manually controlled valve 11 to 65 control the discharge of the fluid therefrom. A suction conduit is connected with the container and is adapted to have its intake end inserted in the casing to be cleaned so that the cleaning fluid, grease and other matter 70 within the casing may be withdrawn therefrom and delivered to the container. This suction line is here shown as comprising a flexible conduit or hose 12 which, if desired, 75 may be provided at its intake end with a nozzle 13 having a manually controlled valve 14.

Connected with this suction conduit 12 and serving to connect the same with the container is an ejector 15, the discharge end of which is arranged within the container. The discharge pipe 8 of the pump is connected with the upper end of the ejector so that a jet of fluid from the pump will be discharged through the ejector and will create therein 80 a suction sufficient to withdraw through the suction conduit 12 fluid and other matter in the casing. In order to increase the efficiency of the ejector I have provided the same with means for so spreading the jet of fluid from the pump that this jet will substantially fill 85 the bore of the ejector, and in the device here shown this means comprises a pin 16 extending through the ejector in the path of the jet of fluid.

90 Because of the considerable quantities of grease contained in the fluid which is discharged into the container 5 this fluid has a tendency when agitated to foam to an extent which is highly objectionable and I have 95 found that by directing the incoming column 100

of fluid from the ejector against the side wall of the container above the level of the liquid therein this foaming can be entirely avoided or reduced to such an extent that it is not 5 objectionable. As here shown, the inner or discharge end of the ejector is provided with a curved deflector 17 so arranged that it will cause the column of fluid to be discharged from the ejector in a substantially horizontal plane against the wall of the container and at an obtuse angle to that wall.

The pump 7 may be mounted within the container in any suitable manner, so long as its intake is submerged. In the present 15 apparatus the pump itself is entirely submerged in the cleaning fluid and it is here shown as connected with the top wall or closure 6 by means of rods 18 and a cylindrical spacing member 19 of relatively large diameter is interposed between the pump and the top wall to maintain the pump in the proper spaced relation to the top wall. A driving shaft 20 is directly connected at its lower 20 end to the pump 7 and extends upwardly through the spacing member 19 and the top wall 6 and is directly connected at its upper 25 end with the shaft of an electric motor 21, the connection being preferably a separable one as shown at 22 to permit of the ready 30 removal of the motor. By thus directly connecting the motor with the pump and eliminating the gears and other intermediate parts which would otherwise be necessary, I greatly 35 simplify the mechanism and so reduce the number of parts therein as to materially decrease the cost of construction and to simplify the maintenance of the apparatus. This 40 direct connection permits the motor to be mounted directly on and centrally of the top wall 6 of the container, thereby providing a very compact and convenient arrangement.

The fluid which is withdrawn from the gear casing which is being cleaned contains 45 hardened grease and other solid matter, and in order to prevent such matter from entering the pump I have provided the latter with a strainer. In that form of the mechanism here shown an inlet casing 23 is connected with the pump intake and provided with a foraminous wall or strainer 24. As here shown, this inlet casing is arranged below and directly connected with the pump. Means are also provided to prevent the grease 50 and other foreign matter in the fluid from accumulating on the strainer to such an extent as to interfere with the free flow of the fluid through the same. This is accomplished by directing a stream or streams of fluid 55 against the strainer, and in the present instance this fluid is taken from the pump independently of the ejector. To this end a second and relatively small discharge pipe 60 is connected with the discharge side of the pump and has a portion 26 extending

across the strainer 24, this portion of the pipe having in each side thereof a series of small holes from which the fluid is discharged across the face of the strainer, thus preventing the grease from adhering to the strainer 70 and washing off any matter which may come in contact with the strainer.

In the present arrangement the apparatus is shown as mounted on a truck consisting of wheels 27 and upright handles 28, whereby 75 the apparatus may be readily transported from one place to another.

While I have shown and described one embodiment of my invention, I wish it to be understood that I do not desire to be limited 80 to the details thereof as various modifications may occur to a person skilled in the art.

Having now fully described my invention, what I claim as new and desire to secure by Letters Patent is:

1. A motor vehicle service station unit for cleaning gear casings and the like, comprising a container for cleaning fluid, a suction line to connect the casing which is to be cleaned with said container, an ejector in said suction line, a pump arranged within said container, and having its inlet immersed in the liquid therein, means including a tubular spacing member for supporting said pump on and in spaced relation to the top wall of said container, a motor supported by said container, and means within said tubular spacing member for establishing a driving connection between said motor and said pump.

2. A motor vehicle service station unit for cleaning gear casings and the like, comprising a container for cleaning fluid, a suction line to communicate with the casing to be cleaned, an ejector connected with said suction line and having its discharge end within said container and arranged to discharge the fluid withdrawn from said casing directly into said container and against the side wall thereof above the level of the liquid therein, a pump communicating with the interior of said container and discharging fluid through said ejector, an inlet casing immersed in the fluid in said container, communicating with the inlet of said pump and having a foraminous wall, and means for operating said pump.

3. A motor vehicle service station unit for cleaning gear casings and the like, comprising a container for cleaning fluid, a pressure line to deliver cleaning fluid to the casing to be cleaned, a suction line to communicate with the casing to be cleaned, an ejector connected with said suction line and having its discharge end extending directly into said container and provided with a curved deflector to discharge the fluid withdrawn from said casing laterally against the side wall of said container above the level of the liquid therein, a pump connected with said pressure

line and said ejector, an inlet casing immersed in the fluid in said container and communicating with the inlet of said pump, and means for operating said pump.

5 4. A motor vehicle service station unit for cleaning gear casings and the like, comprising a container for cleaning fluid, a suction line to communicate with the casing to be cleaned, an ejector connected with said suction line and arranged to discharge the fluid withdrawn from said casing into said container, a pump communicating with the interior of said container and adapted to discharge a jet of fluid through said ejector, a 10 device arranged in the passageway through said ejector to spread said jet of fluid, and means for operating said pump.

15 5. A motor vehicle service station unit for cleaning gear casings and the like, comprising a container for cleaning fluid, a suction line to communicate with the casing to be cleaned, an ejector connected with said suction line and arranged to discharge into said container, a pump communicating with the 20 interior of said container and adapted to discharge a jet of fluid through said ejector, a pin extending through said ejector in the path of said jet and serving to spread the same, and means for operating said pump.

25 6. A motor vehicle service station unit for cleaning gear casings and the like, comprising a container for cleaning fluid, a suction line to communicate with the casing to be cleaned, an ejector connected with said suction line and arranged to discharge the fluid withdrawn from said casing into said container, a pump communicating with the interior of said container and having means to discharge fluid through said ejector, a 30 strainer for separating solid matter from the fluid which enters said pump, means independent of said ejector to discharge fluid from said pump against said strainer to keep the same clean, and means to operate said 35 pump.

40 7. A motor vehicle service station unit for cleaning gear casings and the like, comprising a container for cleaning fluid, a suction line to communicate with the casing to be cleaned, an ejector connected to said suction line and arranged to discharge the fluid withdrawn from said casing into said container, a pump communicating with the interior of said container, a conduit leading from said 45 pump and arranged to discharge fluid through said ejector, a strainer for separating solid matter from the fluid which enters said pump, a second discharge conduit leading from the said pump and arranged to discharge fluid against said strainer to keep the same clean, and means for operating said 50 pump.

55 Signed at Beaver, Pennsylvania, this first day of September, 1927.

60 LEO DEUTSCH.
